UNITED STATES PATENT OFFICE

ROBERT S. PEELE, OF HOLLIS, NEW YORK, ASSIGNOR TO THE PEELE COMPANY, OF BROOKLYN, NEW YORK, A CORPORATION OF NEW YORK

ELECTRICAL INTERLOCK

Application filed October 2, 1929. Serial No. 396,790.

My invention relates to electrical interlocks, and more particularly to an attachment of this character especially adapted for use upon dumbwaiter doors in which the lock bar not only co-operates with a latch member, but actuates the switch mechanism for controlling the power for operating the dumbwaiter.

Electrical interlocks of various types have long been in successful operation, and the general function of such mechanisms is well known. However, not only does the construction of such interlocks vary with different constructions and different types of doors, but local requirements or particular uses satisfied by one type of interlock, may not be satisfied by another type.

The interlock of my present invention was produced to meet a condition requiring the positive mechanical locking of a dumbwaiter door, and the closing of the circuit to the dumbwaiter operating motor, at all times excepting when the dumbwaiter car is adjacent the opening closed by a door. The construction of the lock of my invention is such as to compel a substantially complete closure of the door before power can be applied to the dumbwaiter, and to establish a relation of the latch member and the latch bar prior to the actuation of the switch mechanism, which will preclude any possibility of the door being left in a position to effect the closing of the switch mechanism, and permit subsequent movement of the door sufficiently to allow access to the dumbwaiter car.

By this construction it is impossible, while a dumbwaiter is in motion, for anyone to exercise any control over the dumbwaiter car so as to have access thereto, except during that short interval while the latch mechanism is released by the striker or cam carried by the car.

The shafts for dumbwaiters are ordinarily of small dimensions, and equipment in such shafts is peculiarly subject to fouling from matter falling from the dumbwaiter platform. It being necessary that the interlock mechanism be located within the shaft where dirt may readily accumulate thereon, I so construct the actuating lever of

the switch mechanism that it may have the desired range of movement to ensure reliability in the actuation of the circuit control switch, and at the same time expose, upwardly of the shaft, no spaces about this actuating member sufficient to permit dirt to enter the housing in sufficient quantity to interfere with the proper action of the switch mechanism.

The switch of my invention is so constructed as to not only afford the desired strength and durability of parts necessary in a mechanism subject to the severe usage which automatic devices of this character receive, but its construction and operation are such that likelihood of interference with the operation of the dumbwaiter car is reduced to a minimum, by reason of the short interval of time allowed for what may be termed the "illicit control" of the dumbwaiter, and the impossibility of getting access to the dumbwaiter by an improper use of the door, even though the power to the dumbwaiter be interrupted.

The invention consists primarily in an electrical interlock embodying therein a housing having a slot in the top thereof, fixed electrical contacts within said housing, a vertically extending rocking lever, one arm of which carries a spring pressed movable contact, and the other arm of which projects through said opening in, and extends above, the top of the housing a spring operative upon said lever having a normal tendency to disengage said movable contact from said fixed contacts, a vertically extending rocking latch lever pivoted exteriorly of said housing, and extending upwardly beyond said first named rocking lever in a vertical plane parallel therewith, an impact member carried thereby, a horizontally extending latch bar carried by and movable with a vertically movable door section and a spring operative upon said latch lever with a normal tendency to engage it with said latch bar, a cam member carried by said latch bar in engaging relation with said switch actuating lever, said latch bar being engageable by said latch lever to mechanically lock the dumbwaiter door before said cam is operative upon said rock-

ing lever to engage said electrical contacts and a striker member carried by and movable with a dumbwaiter car co-operating with said impact member to cause the engagement and disengagement of said latch lever with said latch bar according to the position of the dumbwaiter car; and in such other novel features of construction and combination of parts as are hereinafter set forth and described, and more particularly pointed out in the claims hereto appended.

Referring to the drawing,

Fig. 1 is an elevation of a fragmentary portion of a counterbalanced elevator door adjacent the meeting line of the two sections with an electrical interlock embodying the invention applied thereto, the cover of the housing being removed;

Fig. 2 is a view thereof from the left of Fig. 1 showing the striker or cam carried by and movable with the dumbwaiter car, and illustrating in dotted lines the locked and unlocked position of the mechanical locking means embodied in the interlock;

Fig. 3 is a plan view of Fig. 1 with the housing cover in position;

Fig. 4 is a fragmentary portion illustrating the latch bar and the parts co-operating therewith when the door is in the partially open position; and

Fig. 5 is a similar view illustrating the relation of parts shown in Fig. 4, with the latch in position to close the switch mechanism and yet permit the door to be raised sufficiently to actuate said switch mechanism to open the circuit to the dumbwaiter operator mechanism.

Like numerals refer to like parts throughout the several views.

In the embodiment of the invention shown in the drawing, a portion of the upper section of a counterbalanced dumbwaiter door is shown at 10, and a portion of the lower section thereof at 11. These two sections are movable upon vertically extending guides 12, within the dumbwaiter shaft, and have movement in the same vertical plane toward and from each other when opening or closing the door. At 13 I have shown a part of the connections between the two sections.

Dumbwaiter doors of the character to which my invention relates, are old and well known in the art, and a further description thereof is therefore unnecessary.

The dumbwaiter car itself and the means for controlling the movements thereof, aside from that control by the doors through the actuation of the electrical interlock, form no part of the present invention, and requires no detailed description beyond that the control for the motive power for such cars must be electrical in order to permit the use of the type of interlock herein referred to.

Frequently, such dumbwaiter equipment

is so constructed that the controls for the power for actuating the car, may be so set as to cause a car to be moved to, and stopped at, a particular shaft opening, and the electrical interlock of my invention is so constructed and designed as to permit the opening of a door only while the dumbwaiter car is at rest adjacent the opening closed by that door, and to prevent the interruption of power for actuating the car by the opening of the door at any opening other than, what may be termed, the final destination of the car, and access to the car in the event of an attempt to open a door. This will more fully appear hereinafter.

The electrical interlock of my invention embodies a housing 14, which for convenience in wiring the interlock, is provided with a removable closure 15. Within this housing are fixed contacts 16 and 17 arranged in the circuit controlling the movements of the car. The housing 14 has an opening 18 in the top thereof.

Pivottally mounted within the housing 14 is a rocking lever 19, this lever being mounted upon a horizontally extending pivot 20. The lower arm of the lever 19 carries a stud 21, upon which is slidably mounted a bridge contact member 22 cooperating with the fixed contacts 16 and 17. The stud 21 carries a stop pin 23 adjacent its end, and is encircled by a spring 24 bearing against the lever 19 and against the bridge contact member 22. The contact members 16, 17 and 22 are properly insulated in relation to their supports to avoid short circuiting. The other arm of the lever 19 projects through the opening 18 in the top of the housing 14, and has a close sliding fit with the side walls of this opening. The top of this arm is bevelled as indicated at 25.

One arm of the lever 19 is acted upon by a spring 26 having a normal tendency to rock said lever in a manner to disengage the contact 22 from the contacts 16 and 17.

Carried by or formed upon the lever 19 is a shield member 27 of a width to close the major portion of the opening 18 which, when a door is opened, results from the movement of the upper part of the lever 19 toward the wall of the shaft. The top of the housing 14 is provided with a flange 28 bevelled to permit movement of the shield member, and of a thickness and depth to facilitate the attachment of the closure 15 to the housing.

The housing 14 is spaced away from the guide rail structure 12 by means of a bridge 29 to which the housing is secured in any desired manner. This bridge carries a pivot screw 30 mounted upon which is a latch lever 31 projecting above and below the housing 14. The lower arm of this lever is provided with the usual adjustable roller impact member 32, adapted to be engaged by a striker or cam 33 carried by and movable with the dumbwaiter

car. The other arm of this lever is provided with a latch member 34 having two parallel shoulders 35 and 36, the former of which is so positioned as to become operative prior to the engagement of the switch members 16, 17 and 22, and the latter of which is adapted to become operative following such engagement. The purpose for this will more fully appear hereinafter.

power being applied to the dumbwaiter car while access is being had thereto, and to prevent the interruption of such power from floors other than that for which the contents of the dumbwaiter are intended. It has nothing to do with controlling the operation of the car, beyond the negative function above referred to.

Under some conditions, persons for whom the contents of the dumbwaiter are not intended, may attempt to so handle the doors as to permit them to interrupt the power to the car operating mechanism, and one of the purposes of the present invention is to so construct the interlock as to deter this practice by preventing access to the car, even though it may be stopped at an opening closed by a door, the theory being that nobody is going to interfere with the operation of the dumbwaiter unless access can be had thereto after such stoppage.

Assuming that all of the doors in a shaft are closed, all of the switches 16, 17 and 22 in the shaft will also be closed, and power may be applied for raising or lowering the dumbwaiter car.

When a door is properly closed and locked, the position of parts is as shown in Figs 1, 2 and 3. As the car reaches the floor at which it is to stop, the striker member or cam 33 engages the impact member 32 and rocks the latch lever 31 to the position shown in dotted lines in Fig. 2, both shoulders 35 and 36 being moved out of the path of the latch bar 37. The parts remain in this position so long as the car is at rest, thus permitting the door to be freely opened.

With the initial upward movement of the door, the striker member or cam 39 passes from its engaging and restraining relation with the switch lever 19, permitting the spring 26 to rock this lever in a manner to move the contact member 22 out of engagement with the contacts 16 and 17, thus interrupting the circuit to the dumbwaiter car control. So long as the parts are in this position, which is indicated in Fig. 4, power cannot be applied to cause movement of the car. The quantity of movement of the striker member or cam 39, while engaging the bar 19 to thus interrupt the power for actuating the car, is approximately half an inch.

If it were not required to make equipment of this kind as nearly foolproof as possible, a single shoulder 36 could be used upon the latch member. The difficulty is that those using the dumbwaiter, as experience has demonstrated, are very apt to serve their personal convenience, to interfere with the service. Where a lock is accessible from the floor side, and an interlock is used, persons are apt to try to stop the car at a particular opening when the contents of the car are designed for others at another opening. Where, as in the present case, the interlock

10 Carried adjacent the bottom of the upper door section is a latch bar 37, a portion of which is formed, as shown at 38, so as to pass about the angle metal frame of the door section, and about the guide structure 12 into operative relation to the latch member 34 and the switch lever 19. Adjacent said lever, the latch bar 37 is provided with a projecting cam or striker member 39 adapted to engage the bevelled dog 25 of said arm 19. The dimensions of this striker member are such as to be positioned fairly closely to the top of the housing 14 and extend over the exposed portion of the slot 18 when the door is in the closed position.

25 The depth of the bar 37, the formation of the striker member 39 and the location of the shoulder 35 are such that toward the final closing movement of the door, the shoulder 35 passes over the top of the latch bar 37 before the cam 39 has oscillated the lever 19 to an extent to engage the contact 22 with the contacts 16 and 17. As the door reaches the fully closed position, the striker member or cam 39 will have oscillated the lever 19 to an extent to properly engage the contact 22 with the contacts 16 and 17, and the shoulder 36 will have passed over and engaged the lock bar 37.

30 The latch lever 31 is acted upon by a spring 40, the function of which is to move the latch lever in a direction to engage the latch member 34 with the lock bar, and to position the impact member 32 in the path of movement of the striker member or cam 33 upon the car.

45 The operation of the herein described electrical interlock is substantially as follows:—

All of the dumbwaiter doors in a shaft should, at all times, except when access is to be had to the dumbwaiter car, be closed and locked, and the opening of any door from the floor of a building, should be prevented except when the car is opposite the opening at a particular floor.

50 Dumbwaiter doors of the type to which my invention relates, are generally used in public, or quasi-public, buildings, such as hospitals, schools, churches, restaurants, hotels, apartment houses, etc., and the character of the dumbwaiter installation is usually such that the point of stoppage of the car may be controlled at the time that power is applied to the car.

55 With installations of the character above referred to, the electrical interlock of my invention is used for the purpose of preventing

and lock are full automatic, and located within the shaft where they are not accessible from the floor, such a person will endeavor to instantly open the door while the striker or cam 33 is operative upon the latch member 31. This interval, however, is very short, since the operative surface of the cam 33 may be only an inch or two and the dumbwaiter car has fairly high speed. Consequently, in closing the door, a person trying to, what is known as "steal" the car, will endeavor to move the upper section 10 downwardly to an extent to close the circuit through the contacts, and yet not have the mechanical latch member operate to lock the door.

With this condition, were it not for the shoulder 35, it would be possible, by a fairly slow movement of the door, to open the door and stop the car entirely independently of an actuation of the latch member by the striker or cam 33. The shoulder 35 is used so that the mechanical locking of the door will be assured upon the switch bar 19 being actuated to an extent to engage the contact 22 and the contacts 16 and 17, and hence the door will be mechanically locked upon power being applied to the car to move it. This condition is shown in Fig. 5.

It is impracticable, in equipment of the character to which my invention relates, to so nicely construct and adjust the parts as to avoid a certain amount of leeway or lost motion not desirable in the device, but necessary because of conditions surrounding devices of this character. In the device of the present application, there is a leeway of approximately a quarter of an inch before the engagement of the shoulder 36 with the latch bar, during which the circuit to the elevator controls are closed, and this leeway is what a user might take advantage of, were it not for the use of the shoulder 35.

It will be noted, by reference to Fig. 5 of the drawing, that while the latch bar is not engaged with the shoulder 35, it is also not engaged with the shoulder 36, and that the contact member 22 is not engaged with the contacts 16 and 17. Slight additional downward movement of the door, not enough to cause the engagement of the shoulder 36 with the latch bar 37, will nevertheless cause the engagement of the contact 22 with the contacts 16 and 17. It will also be noted that this condition will permit the opening and closing of the circuit to the power for actuating the car.

When the door has been thus moved downward slightly, without engaging the shoulder 36 with the latch bar 37, it may be restored to the position shown in Fig. 5 at any time, and thus actuate the movable contact member to interrupt the power to the car. By reason of the engagement of the bar 37 with the shoulder 35, however, even though a person might succeed in stopping the car, the door cannot

be opened sufficiently to permit access thereto. This condition will discourage the practice of interfering with the service in the manner above referred to, and will tend to ensure the complete closing of the doors at all times.

The use of the rocking lever 19 passing through and having a close sliding fit in the opening 18 in the top of the housing 14, of the wide cam or striker member 39, and of the shield member 27, will, at all times, afford a substantially continuous barrier above said opening 18, so that in washing down or painting the shaft, or in the event of matter dropping from the car platform, foreign substances will be excluded from the housing 14.

The use of the rocking lever 19 and the actuating striker or cam 39 co-operating therewith, not only ensures a positive actuation of the switch mechanism, but minimizes the tendency toward a rebound of the door to an extent to avoid a possible failure of the shoulder 36 to engage the latch bar 37.

It will be noted that tampering with the interlock is impossible, since it is located within the shaft, and access cannot be had thereto while the door is closed, nor while the door is open, since the side walls of the dumbwaiter car will prevent such access being had to the interlock while the door is open, and the door cannot be opened unless a car is so located as to prevent such access. If a skeleton car should be used, which ordinarily is not the practice, tampering with the interlock would serve no useful purpose, since with dumbwaiter doors, the permanent blocking of the lever 19 when the circuit is closed by the switch mechanism controlled thereby, would not aid in securing access to the car, but rather defeat this object.

An interlock embodying the invention is particularly adapted for use under those conditions where a positive mechanical locking of the door is required before the circuit controlling the operation of the car is closed, this being secured by the presence of the shoulder 35 which, as heretofore stated, becomes operative to prevent the re-opening of the door before the contact 22 is engaged with the contacts 16 and 17.

It is not my intention to limit the invention to the precise details of construction shown in the drawing, it being apparent that such may be varied without departing from the spirit and scope of the invention.

Having described the invention, what I claim as new and desire to have protected by Letters Patent, is:—

1. An electrical interlock embodying there-in a housing having a slot in the top thereof, fixed electrical contacts within said housing, a vertically extending rocking lever, one arm of which carries a spring pressed movable contact, and the other arm of which projects through said opening in, and extends above,

the top of the housing, a spring operative upon said lever having a normal tendency to disengage said movable contact from said fixed contacts, a vertically extending rocking 5 latch lever pivoted exteriorly of said housing and extending upwardly beyond said first named lever in a vertical plane parallel therewith, an impact member carried thereby, a latch bar carried by and movable with a vertically movable door section and a spring operative upon said latch lever with a normal tendency to engage it with said latch bar, a cam member carried by said latch bar in engaging relation with said switch actuating 10 lever, said latch bar being engageable by said latch lever to mechanically lock the dumbwaiter door before said cam is operative upon said rocking lever to engage said electrical contacts, and a striker member carried 15 by and movable with a dumbwaiter car cooperating with said impact member to cause the engagement and disengagement of said latch lever with said latch bar according to 20 the position of the dumbwaiter car.

2. An electrical interlock embodying therein a housing having a slot in the top thereof, fixed electrical contacts within said housing, a rocking lever, one arm of which carries a spring pressed movable contact, and 25 the other arm of which projects through said opening in the top of the housing, a rocking latch lever pivoted exteriorly of said housing, said latch lever having a plurality of spaced parallel shoulders, an impact member carried thereby, a latch bar carried by and movable with a vertically movable door section, and a cam member carried by said latch bar in engaging relation with said switch actuating lever, said latch bar being 30 engageable by one of the shoulders of said latch lever to mechanically lock the door prior to the engagement of said movable contact with said fixed contacts, and by the other 35 of said shoulders after such engagement.

3. An electrical interlock embodying therein a housing having a slot in the top thereof, fixed electrical contacts within said housing, a rocking lever, one arm of which carries a spring pressed movable contact, and 40 the other arm of which projects through and has a close sliding fit in said opening in the top of the housing, a rocking latch lever pivoted exteriorly of said housing, an impact member carried thereby, a latch bar carried by and movable with a vertically movable door section, and a cam member carried by said latch bar in engaging relation with said switch actuating lever, said cam member being 45 of dimensions to shield the portion of said slot resulting from the actuation of said lever, said latch bar being engageable by said latch lever to mechanically lock the dumbwaiter door.

4. An electrical interlock embodying therein a housing having a slot in the top

thereof, fixed electrical contacts within said housing, a rocking lever, one arm of which carries a spring pressed movable contact, and the other arm of which projects through and has a close sliding fit in said opening in the 50 top of the housing, a shield carried by and movable with said rocking lever, the dimensions of which are such as to substantially close the portion of the slot exposed by the movement of said lever when a door is open, a rocking latch lever pivoted exteriorly of 55 said housing, an impact member carried thereby, a latch bar carried by and movable with a vertically movable door section, and a cam member carried by said latch bar in engaging relation with said switch actuating lever, said cam member being of dimensions to shield the portion of said slot resulting from the actuation of said lever, said latch bar being engageable by said latch lever to 60 mechanically lock the dumb-waiter door.

5. An electrical interlock embodying therein a housing having a slot in the top thereof, fixed electrical contacts within said housing, a rocking lever, one arm of which carries a spring pressed movable contact, and the other arm of which projects through and has a close sliding fit in said opening in the 65 top of the housing, a rocking latch lever pivoted exteriorly of said housing, said latch lever having a plurality of spaced parallel shoulders, an impact member carried thereby, a latch bar carried by and movable with a vertically movable door section, and a cam member carried by said latch bar in engaging relation with said switch actuating lever, said cam member being of dimensions to shield the portion of said slot resulting from the actuation of said lever, said latch bar being engageable by one of the shoulders of 70 said latch lever to mechanically lock the door prior to the engagement of said movable contact with said fixed contacts, and by the other of said shoulders after such engagement.

6. An electrical interlock embodying therein a housing having a slot in the top thereof, fixed electrical contacts within said housing, a rocking lever, one arm of which carries a spring pressed movable contact, and the other arm of which projects through and has a close sliding fit in said opening in the 75 top of the housing, a shield carried by and movable with said rocking lever, the dimensions of which are such as to substantially close the portion of the slot exposed by the movement of said lever when a door is open, a rocking latch lever pivoted exteriorly of 80 said housing, said latch lever having a plurality of spaced parallel shoulders, an impact member carried thereby, a latch bar carried by and movable with a vertically movable door section, and a cam member carried by said latch bar in engaging relation with said switch actuating lever, said cam member being of dimensions to shield the portion of said slot resulting from the actuation of said lever, said latch bar being engageable by said latch lever to 85 mechanically lock the dumb-waiter door.

130

said slot resulting from the actuation of said lever, said latch bar being engageable by one of the shoulders of said latch lever to mechanically lock the door prior to the engagement of said movable contact with said fixed contacts, and by the other of said shoulders after such engagement.

In witness whereof I have hereunto affixed my signature, this 28th day of September, 1929.

ROBERT S. PEELLE.
